UNITED STATES PATENT OFFICE.

LLOYD N. DIBERT, OF SAN FRANCISCO, CALIFORNIA.

GRAIN-BEARDER.

1,385,071.

Specification of Letters Patent. Patented July 19, 1921.

Application filed February 12, 1921. Serial No. 444,526.

To all whom it may concern:

Be it known that I, LLOYD N. DIBERT, a citizen of the United States, residing in the city and county of San Francisco and State 5 of California, have invented certain new and useful Improvements in Grain-Bearders, of which the following is a specification.

My invention relates, in general, to grain-handling machinery, especially for preparatory work to place the grain in proper condition for subsequent operations, such, for example, as separating, cleaning, scouring, grinding, elevating, conveying, etc.

In particular, my invention relates to that 15 class of preparatory grain-handling machines, known in the art as "bearders," the primary function of which, as the name implies, is to tear or break off the beards of such grains as barley and rice, or to so treat 20 or act upon any grains, as, for example, to break the straw joints, smut balls, etc., as to reduce them to condition to enable the elevators, separators, scourers and the like to properly handle them; or to clip oats, or to 25 separate into individuals a mass of grain clinging together after a bran scouring operation.

Although these machines may be applied 30 to such various uses, their special application is the breaking of beards from barley and rice, and as they are known as "barley bearders," I shall herein, for the sake of simplicity refer to my invention, and describe its use in terms of barley.

Barley bearders comprise an elongated drum horizontally disposed, having in its top, near one end, a feed hopper, and in its other end a discharge gate.

Into the drum from each side project radially 40 a line of spaced fixed spikes. In the ends or heads of the drum is mounted a shaft, which is rotated by means of power applied to a pulley on the shaft, said shaft extending through the drum in the axis 45 thereof. The shaft, within the drum, carries a series of spaced and staggered spikes which play between the fixed spikes carried by the drum. The fixed and the revolving spikes coöperate to tear or break off the 50 beards from the barley, and both beards and barley are delivered from the discharge gate, to be subsequently conveniently separated.

In common practice the drum of the bearder comprises two heads, a longitudinally 55 divided sectional peripheral jacket seated in grooves in the heads, and longitudi-

dinal bolts tying the heads together and holding the jacket in its seat. In order to obtain access to the interior of the drum, for any purpose, it is necessary to take out the 60 tie-bolts, and remove the heads, in order to separate the sections of the jacket. This practically requires the dismemberment of the machine, and as the rotating spike-shaft is mounted in the heads, this member of the 65 machine is also affected and its adjustment disturbed.

To overcome this difficulty of gaining access to the interior of the machine, is the object of my invention, and to this end my 70 invention consists in a novel construction of the drum which permits the ready removal and replacement of the jacket or any of its sections without disturbing the heads and the adjustment of the spike-shaft therein. 75

Referring to the accompanying drawings—

Figure 1 is an elevation of my barley-bearder.

Fig. 2 is a top plan view of the same, with 80 the upper section or cover of the jacket removed.

Fig. 3 is an end view from the line 3—3 of Fig. 2, looking in the direction of the arrows.

Fig. 4 is a cross section on the line 4—4 of Fig. 2.

The heads 1 of the drum are cast with feet 2, the upper portions of the latter being formed with angle-shoulders 3. Upon the 90 shoulders 3 are bolted the angle-tie-bars 4 which extend between and connect the heads rigidly together. There is one of these tie-bars 4 on each side. 5 is the jacket. This comprises a plurality of sections, here shown 95 as a top or cover section and a bottom section. The jacket may be of sheet iron or of wire cloth, or in some cases of both; sheet iron being herein indicated.

The heads 1 are cast with an annular 100 rabbet 1', Fig. 2, on their inner faces at their rims, and upon these rabbets the ends of the jacket sections lie. They are held to their seats by a plurality of semicircular straps 6, here shown as comprising three pairs, one 105 member of each pair embracing the top or cover section of the jacket and the other member embracing the bottom section. The ends of the upper straps are bent outwardly over the vertical leg of the angle-tie bars 4 110 and lie upon the upper surface of the horizontal leg of said bars, while the ends of

the lower straps lie up against the under surface of said horizontal legs. These ends, above and below, are secured to said horizontal legs by bolts 7.

5 8 are fixed spikes which project radially into the drum. These are formed with shanks 9 which pass outwardly through the vertical legs of the angle tie-bars 4 and receive nuts 10 by which they are held.

10 11 are reinforcing guide-plates fitted upon the shanks 9 of the spikes 8, and lying along and tight-up against the inner surface of the vertical legs of the angle tie-bars 4. These plates 11 have sufficient width to enable them, both above and below their line of fastening to be bent inwardly, as seen in Fig. 4, thereby forming groove seats in which the side edges of the jacket sections fit to form proper peripheral joints—Fig. 4.

15 20 12 is a shaft having a pulley 13 for rotating it. The shaft is mounted in suitable bearings 14 carried by the heads 1, and it passes through the drum in its axis. It carries the spikes 15. The upper section of the jacket has a feed hopper 16, and one of the heads 1 has a discharge gate 17—Fig. 3.

25 It will now be seen that to gain access to the interior of the machine, all that need be done is to take out the bolts 7 and remove 30 the straps 6. The jacket, or either section of it, may then be lifted or dropped from its seat on the rabbets 1' of the heads and from its groove seats between the guide plates 11 and the tie-bars 4; and this removal does 35 not affect, in any way, the remainder of the machine, as the heads are rigidly connected by the tie-bars and the spike-shaft is not disturbed.

I claim:

40 1. A grain-bearder comprising spaced heads having rabbet-shoulders; tie-plates rigidly connecting said heads; a sectional peripheral jacket extending between and resting on the rabbet-shoulders of the heads; 45 straps embracing the jacket and detachably connected with the tie-plates; spikes carried by and extending from the tie-plates into the space inclosed by the jacket; a rotatable shaft mounted in the heads and passing through said space in the axis thereof; and spikes carried by said shaft.

50 55 2. A grain-bearder comprising spaced heads having rabbet-shoulders; tie-plates rigidly connecting said heads; a sectional peripheral jacket extending between and resting on the rabbet-shoulders of the heads;

straps embracing the jacket and detachably connected with the tie-plates; spikes carried by and extending from the tie-plates into the space inclosed by the jacket; guide plates 60 secured by said spikes to the inner faces of the tie plates and spaced therefrom to form groove seats for the side edges of the jacket sections; a rotatable shaft mounted in the heads and passing through the space 65 inclosed by the jacket in the axis thereof; and spikes carried by said shaft.

3. A grain-bearder comprising spaced heads having rabbet-shoulders, said heads being formed with foot members provided 70 with angle-shoulders; angle tie-plates secured upon said angle-shoulders and rigidly connecting said heads; a longitudinally divided sectional peripheral jacket extending 75 between and resting on the rabbet shoulders of the heads; a pair of straps embracing the sections of said jacket, above and below, the ends of said straps being bolted to the horizontal leg of the angle tie plates; spikes carried by the vertical legs of said tie-plates 80 and extending therefrom into the space inclosed by the jacket; a rotatable shaft mounted in the heads and passing through said space in the axis thereof; and spikes carried by said shaft.

4. A grain-bearder comprising spaced heads having rabbet-shoulders, said heads being formed with foot members provided 90 with angle-shoulders; angle tie-plates secured upon said angle-shoulders and rigidly connecting said heads; a longitudinally divided sectional peripheral jacket extending 95 between and resting on the rabbet shoulders of the heads; a pair of straps embracing the sections of said jacket, above and below, the 100 ends of said straps being bolted to the horizontal leg of the angle tie plates; spikes carried by the vertical legs of said tie-plates and extending therefrom into the space inclosed by the jacket; a rotatable shaft mounted in the heads and passing through said space in the axis thereof; spikes carried by said shaft; and guide plates secured to the inner faces of the vertical legs of the tie plates by the spikes carried by said legs, said plates being spaced from said inner faces to 105 form groove seats for the side edges of the jacket sections.

In testimony whereof I have signed my name to this specification.

LLOYD N. DIBERT.
